UNITED STATES PATENT OFFICE

CHARLES OTTO KNUUTI, OF BERWYN, ILLINOIS, ASSIGNOR TO WESTERN ELECTRIC COMPANY, INCORPORATED, OF NEW YORK, N. Y., A CORPORATION OF NEW YORK

APPARATUS FOR PRODUCING ELECTRICAL CONNECTING ELEMENTS

Application filed February 19, 1929. Serial No. 341,265.

This invention relates to apparatus for producing electrical connecting elements, and more particularly to apparatus for producing short insulated strap wires for interconnecting electrical apparatus.

An object of the invention is to provide a simple and efficient apparatus whereby insulated electrical connecting elements of predetermined length may be produced economically and with a minimum amount of manual labor.

In accordance with the above object there is provided in one embodiment of the invention, an apparatus for producing short insulated strap wires, wherein an insulated electrical conductor is advanced from a supply thereof through a pair of open jaw members, whereupon the movement of a hand lever in one direction serves to close the jaw members so as to grip the conductor therebetween. A severing blade movable with one of the jaw members severs a portion of predetermined length from the end of the conductor. By a further movement of the hand lever in the same direction the severed portion of the conductor is carried into a pair of spaced slotted knives which sever the insulation at predetermined positions spaced from the ends of the conductor and thereafter move apart to strip the severed end portions of the insulation, thereby producing a strap wire having bared conductor ends of predetermined length. Upon the release of the hand lever the parts return to their normal or starting positions, whereupon the finished strap wire is ejected and the above described cycle of operation is repeated.

A more complete understanding of the invention will be had from the following detailed description taken in conjunction with the accompanying drawings, wherein—

Fig. 1 is a rear elevational view partly in section of an apparatus embodying the features of the invention;

Fig. 2 is a vertical section taken substantially on line 2—2 of Fig. 1, with the jaw members shown in their open positions;

Figs. 3 and 4 are fragmentary plan and side elevational views, respectively, of a

portion of the structure shown in Figs. 1 and 2, with the jaw members shown in their closed positions;

Fig. 5 is a fragmentary plan section showing the cam which operates the jaw members;

Fig. 6 is an enlarged detail section taken on line 6—6 of Fig. 1, and

Fig. 7 is a detail view of a strap wire produced by the apparatus shown in Figs. 1 to 6, inclusive.

Referring now to the drawings wherein like reference characters designate corresponding parts throughout the several views, it will be observed that a main supporting frame, indicated generally by the reference numeral 10, is adapted to be attached to a supporting standard 11 by means of suitable screws or bolts 12 (Fig. 2). A pair of cooperating jaw members, hereinafter referred to as the upper and lower jaw members 14 and 15, respectively, are mounted upon a pin or stud shaft 16 rotatably journaled in a pair of spaced ears or lugs 17—17 projecting upwardly from the supporting frame 10.

The upper jaw member 14 is provided at one end with a portion 18 of reduced width extending downwardly at right angles from the main portion thereof whereby it is secured to the shaft 16 so as to be rotatable therewith. The lower jaw member 15 is pivoted at one end upon the shaft 16, the pivoted end thereof being bifurcated, as indicated at 19 (Fig. 3), so as to straddle the reduced portion 18 of the upper jaw member. The upper and lower jaw members are provided with cooperating semi-circular slots or grooves 20—20 for accommodating an insulated electrical conductor 22 drawn from a supply (not shown). A spring pressed pin 23 mounted in a recess 24 provided in the lower jaw member and bearing upwardly against the bottom of the upper jaw member serves to normally hold the jaw members in an open position, as shown in Fig. 2.

Arms 25—25 projecting outwardly from the bifurcated end of the lower jaw member are adapted to engage adjustable stop pins 26, 26 threaded in the frame 10 for limiting

the counter-clockwise movement of the lower jaw member (Fig. 2). A vertically reciprocable plunger 28 bears upwardly against the bottom of the lower jaw member under the pressure of a compression spring 29 whereby the lower jaw member is normally held in the position shown in Fig. 2, wherein the arms 25 engage the stop pins 26. A downwardly projecting arm 30 formed integral with the upper jaw member 14 extends through an elongated slot 31 in the frame 10 and into a notch 32 in a horizontal plunger 33 slidably journaled in the frame. A reduced end portion 34 of the plunger 33 projects outwardly from the frame and carries a roller 35 adapted to be engaged by a face cam 37 formed at the upper end of an operating lever 38. The lever 38 is secured to a reduced end portion of a horizontal shaft 40 rotatably journaled in the frame 10 and is provided with a suitable handle 41 positioned within convenient reach of an operator. It will be observed that upon the movement of the lever 38 in a counter-clockwise direction (Fig. 1), the plunger 33 is moved to the left by the cam 37 (Fig. 2), thereby moving the upper jaw member 14 in a clockwise direction. The movement of the lever 38 is limited in either direction by resilient stops 43 and 44 secured to the frame 10. Secured to an arm 45 projecting transversely from the upper jaw member 14 is a severing blade 46 designed and arranged to sever a predetermined length from the end of the conductor upon the downward movement 35 of the upper jaw member.

A pair of vertically disposed levers 48-48 are pivoted at one end upon spaced pins 49-49 secured to the frame 10 and projecting outwardly from the rear face thereof. It will be noted that the frame 10 is cut away, as indicated at 50 (Fig. 1) to permit the free movement of the levers 48 between the frame and the supporting standard 11. A helical spring 51 secured at opposite ends to pins 52-52 carried by the levers 48 serves to normally urge the levers toward each other against opposite sides of a cam 53 secured to a reduced end portion 54 of the shaft 40. The cam 53 is designed so that upon the movement of the operating lever 38 in a counter-clockwise direction (Fig. 1), the upper ends of the levers 48 are spread apart in opposition to the tension of the spring 51. The upper end of each of the levers 48 is bifurcated and carries an insulation cutting and stripping knife 56. These knives are provided with substantially V-shaped notches 57-57 for receiving the conductor, the notches having cutting edges designed to sever the insulation on the conductor as it is inserted in the grooves by the downward movement of the jaw members as hereinafter described. It will be understood that the severed portions of the insulation are stripped from the ends of the conductor by the knives

56 as they are moved outwardly by the cam 53.

A pair of oppositely disposed angular guide fingers 58-58 are pivoted at one end to opposite sides of the upper jaw member 14 (Fig. 3). The free ends of the guide fingers 58 are slotted, as indicated at 59 (Fig. 4) to accommodate the insulated conductor 22. A helical spring 60 serves to normally urge the guide fingers 58 toward each other and against stop pins 61-61 secured to opposite sides of the lower jaw member 15. As shown in Fig. 1, the guide fingers 58 are spaced from the jaw members so as to accommodate the stripping knives 56 therebetween. By this construction, the guide fingers 58 cooperate with the jaw members 14 and 15 to prevent the bending of the conductor when it is inserted in the slots 57 of the strippers. During the stripping operation, the guide fingers 58 are moved outwardly by the strippers 56 and are returned to their normal positions by the spring 60 upon the return movement of the strippers.

A pair of ejecting members 62-62 are pivoted at their upper ends to opposite sides of an upwardly extending arm 63 formed integral with the upper jaw member 14. The upper and lower jaw members are provided with spaced slots 64-64 for accommodating the lower portions of the ejecting members 62. It will be understood by referring to Fig. 2 that the ejecting members are provided with reduced lower end portions 65-65 designed to extend downwardly behind the conductor 22 positioned between the jaw members. Portions 67-67 extending transversely from the ejecting members 62 are adapted to engage adjustable pins 68-68 carried by a vertical bracket 69 secured to the frame 10. The construction is such that during the last portion of the counter-clockwise movement of the upper jaw member 14 (Fig. 2), the ejecting members 62 are rocked in a counter-clockwise direction due to their engagement with the pins 68, whereby the completed strap wire is ejected from the open jaw members and the cooperating guide fingers 58. After engaging the stop 44, the lever 38 is momentarily released by the operator whereupon a spring pressed plunger 70 (Fig. 1) returns the lever to its normal or starting position. This slight movement of the lever 38 lowers the upper jaw member sufficiently to release the ejecting members 62 from engagement with the pins 68 whereupon a leaf spring 71 returns the ejecting members to their normal positions. One end of the leaf spring 71 is secured to the arm 63 of the upper jaw member and the opposite end thereof presses against a pin 72 interconnecting the ejecting members.

Means is provided for intermittently advancing a predetermined length of the conductor 22 through the upper and lower jaw

members 14 and 15 and the cooperating guide fingers 58. Mounted in a bracket 73 secured to the frame 10 is a horizontal guide tube 74, one end of which extends to the cutting edge 5 of the severing blade 46. A sleeve 75 is slideable on the tube 74 and is provided with oppositely disposed slots 76-76 which register with slots 77-77 formed in the guide tube 74. Gripping fingers 78-78 are arranged 10 to be freely movable in the slots 76 and 77 and are secured to the free ends of leaf springs 79-79 attached to the sleeve 75, the leaf springs serving to normally hold the gripping fingers disengaged from the conductor, as shown in Fig. 1. By pressing the gripping fingers 78 toward each other the conductor is firmly gripped therebetween and may then be readily advanced through the jaw members 14 and 15 by moving the sleeve 20 75 toward the bracket 73. Movement of the sleeve 75 is limited on the forward stroke by the bracket 73 and its movement on the return stroke is limited by a stop collar 80 which is adjustable along the tube 74 whereby 25 the length of feed may be varied to produce strap wires of various lengths. A dog 81 pivoted in a slot 82 formed in the bracket 73 is arranged to grip the conductor so as to prevent movement thereof during the return 30 movement of the sleeve 75. It will be understood, of course, that various other means may be employed for intermittently advancing the conductor. For example, the conductor may be fed by hand against a measuring stop 84 secured to the frame 10.

In the operation of the above described apparatus, a predetermined length of the conductor is advanced through the normally open jaw members 14 and 15 and the cooperating guide fingers 58 in the manner hereinbefore described. The lever 38 is thereafter moved in a counter-clockwise direction (Fig. 1) thus closing the jaw members 14 and 15 and thereafter causing them to be moved 45 downwardly (Fig. 2) to the position shown in Fig. 4. During this movement of the jaw members, a portion of predetermined length is severed from the end of the conductor by the severing blade 46 and the severed portion is inserted in the slots 57 of the strippers 56, whereupon the strippers are simultaneously moved outwardly by the cam 53, thereby stripping the insulation from the ends of the conductor. Upon the return 50 movement of the lever 38 the strippers 56 are returned to their normal positions by the spring 51, and the jaw members 14 and 15 are moved upwardly by the plunger 28, the lower jaw member stopping at the position shown in Fig. 2, and the upper jaw member continuing to move upwardly until the plunger 33 reaches the end of its travel to the right. By this extra movement of the upper jaw member the completed strap wire is released 55 and ejected by the members 62, as herein-

before described. The lever 38 is then momentarily released whereupon it is returned to its normal or starting position by the spring pressed plunger 70 (Fig. 1) thereby permitting the ejecting members 62 to return to their normal positions under the pressure of the spring 71.

The completed strap wires, one of which is shown in Fig. 7, comprise a central insulated portion 85 and bared conductor end portions 86-86 of predetermined length, and may be used for interconnecting parts of electrical apparatus. If desired, the stripped sections of insulation may be collected and used as insulating sleeves for lead-in wires 60 in the manufacture of electrical coils and the like.

It is to be understood that the embodiment of the invention herein illustrated and described is merely a convenient and useful form of the invention which is capable of various modifications without departing from the spirit and scope of the invention.

What is claimed is:

1. In an apparatus for producing insulated electrical connecting elements from an insulated electrical conductor, a pair of cooperating jaw members for gripping an end portion of the conductor, means carried by one of the jaw members for severing a portion from the conductor, a pair of spaced stripping members having slots for receiving the severed portion of the conductor, and means for moving the stripping members away from each other and away from said jaw members to remove the insulation from the end portions of the conductor.

2. In an apparatus for producing electrical connecting elements from an insulated electrical conductor, means whereby the conductor may be advanced, spaced stripping members having recesses therein for receiving the conductor, a pair of jaw members disposed between said stripping members, resilient means for normally holding the jaw members in an open position for receiving the conductor when advanced, means for closing the jaw members for holding the conductor and for moving the conductor into the recesses in said stripping members.

3. In an apparatus for producing an insulated electrical connecting element from an insulated electrical conductor, a pair of spaced stripping members for cutting the insulation at predetermined positions spaced from the respective ends of the conductor section, and means for moving the stripping members outwardly simultaneously to or past the ends of said section to remove the severed end portions of the insulation from the ends of the section.

4. In an apparatus for producing electrical connecting elements from an insulated electrical conductor, spaced apart stripping members having recesses for receiving a conduc-

tor and for cutting the insulation at the point of reception, means for moving said stripping members with respect to the conductor for stripping the insulation from the ends thereof, and means for removing the conductor from said stripping members.

5. In an apparatus for producing electrical connecting elements from an insulated electrical conductor, spaced apart stripping members having recesses for receiving a conductor and for cutting the insulation at the point of reception, means for moving said stripping members with respect to the conductor for stripping the insulation from the ends thereof, means for removing the conductor from said stripping members, and means for discharging the stripped conductor.

6. In an apparatus for producing electrical connecting elements from an insulated electrical conductor, spaced apart stripping members having recesses for receiving a conductor and for cutting the insulation at the point of reception, means for placing the conductor in the recesses, means for moving said stripping members with respect to the conductor, and means for holding the conductor against bending.

7. In an apparatus for producing electrical connecting elements from an insulated electrical conductor, spaced apart stripping members having recesses for receiving a conductor and for cutting the insulation at the point of reception, means for placing the conductor in the recesses, means for moving said stripping members with respect to the conductor for stripping the insulation from the ends thereof, and means for automatically removing the conductor from said stripping member.

40 8. In an apparatus for producing electrical connecting elements from an insulated electrical conductor, means for receiving the conductor, a gripping member normally disposed adjacent said receiving means for receiving a portion of the conductor, a plurality of stripping members, means for actuating said gripping member for gripping the conductor and for bringing the conductor portion into engagement with the stripping members, and means carried by said gripping member and cooperating with said receiving means for severing the portion from the conductor during its movement imparted by the gripping member, and means for moving the stripping members away from each other and from the gripping member to remove insulation from each end of the conductor portion.

55 9. In an apparatus for producing an electrical connecting element from an insulated electrical conductor, a pair of stripping members, means for gripping the conductor to hold it straight and for moving it into engagement with the stripping members, and means for moving the stripping members away from each other and from the gripping

means to remove simultaneously a predetermined portion of insulation from each end of the conductor to produce a straight connecting element.

10. In an apparatus for producing an electrical connecting element from an insulated electrical conductor, a pair of members for cutting portions of the insulation on the conductor, means for holding the conductor in a straight line and for bringing it into engagement with the members, means for moving the members in opposite directions relative to the conductor holding means to remove insulation from each end of the conductor to produce a straight connecting element, and means for ejecting the completed connecting element from said members.

In witness whereof I hereunto subscribe my name this 6th day of February A. D. 1929.

CHARLES OTTO KNUUTI.
